RIVETING MACHINE

Arthur R. Havener, Wayland, Mass., assignor to
 Judson L. Thomson Manufacturing Company,
 Waltham, Mass., a corporation of Massachusetts

Application April 25, 1939, Serial No. 269,926

11 Claims. (Cl. 218—2)

This invention relates to machines for setting rivets or similar fastenings and has for an object to provide improved and simplified means for controlling and moving the rivet holder in time with the rivet-driving mechanism and in a differential relation thereto and without requiring the use of cams or other complicated mechanism. Such means is so arranged that as the rivet driver first moves downwardly close to the head of the rivet in the holder, the holder moves in unison with the driver until it is close to the work, whereupon it stops and the driver continues its downward journey to drive the rivet out of the holder and to set it in the work. This is preferably accomplished by a pair of slides, one mounted on the driving means and movable therewith, and the other frictionally connected to it in overlapping relation and adapted to move the holder at the appropriate time. When the holder engages a stop, then the frictional connection between the two slides permits relative movement between them. The provision of this means contributes in a large measure to the simplification of the machine and eliminates all cams and other parts necessitated by cams, and permits the use of a simple crank arm as the operating means.

A further improvement resides in a simplified mechanism for actuating the rivet separator which insures the proper presentation of rivets to the holder and driver.

Further objects and advantages will appear from a more complete description of certain embodiments of this invention shown in the accompanying drawings in which

Figure 1 is a right side elevation of the forward portion of a riveting machine embodying this invention.

Figure 2 is an exploded perspective view of a friction device used in the construction shown in Figure 1.

Figure 3 is a view partly in front elevation and partly in section on line 3—3 of Figure 1.

Figure 4 is a detail section on line 4—4 of Figure 3.

Figure 5 is a view similar to Figure 4, but showing the parts in different positions.

Referring to these figures, at 150 is shown the ram to the lower end of which is secured the rivet set or driver 151. This ram is vertically slidable through a sleeve portion 152 of the frame and also extends into the upper portion of the rivet holder support 153 within which it is slidably guided. This rivet holder support 153 carries at its lower end a rivet holder comprising a pair of jaws 154 which directly support the rivet, these

jaws being mounted for yielding motion from each other sufficient to permit the rivet as at 155 to be forced downwardly between them into the work. These jaws are shown as carried by strips 156 which may be yieldable in themselves or may be so mounted as to be movable to open and close the jaws in the well known manner. The rivet holder support 153 is shown as provided with a pair of lateral extensions 157 and 158 through which extends a rod or pin 160, this pin extending completely through the support 153. On the right hand end of this pin 160 there is mounted a slide 161, which as shown best in Figures 4 and 5, is provided with a slot 162 through which the pin 160 projects. A washer 163 secured to the adjacent end of the pin 160 as by a screw 164 secures the block or slide 161 in position on the pin 160 but with capability of lost motion relative thereto by reason of the slot 162. The extent of this lost motion in an upward direction of motion of the slide 161 may be adjustably fixed as by a stop screw 165 which may impinge on a pin 166 projecting outwardly from the sleeve portion 152. The lower limit of motion of the slide 161 with respect to the rivet holder support 153 is determined by the upper end of the slot 162. In overlapping relation to the slide 161 and the rivet holder support is arranged a rivet holder driver 170. This driver is formed as a flat bar, the upper end of which is provided with a boss 171 which fits on a transverse pivot pin 172 which secures the upper end of the ram 150 to the forward end of an actuating arm 173 which may be rocked downwardly as by a crank (not shown) operatively connecting to its opposite end in order to actuate the ram 150. The mounting and actuation of this arm may be similar to that shown in my Patent No. 1,276,652 granted August 20, 1918. The driver 170 is slotted centrally throughout the major portion of its length as at 175 and through this slot extends a screw 176. As shown best in Figures 2 and 3, this screw 176 is carried by the slide or block 161 and extends through a channel portion 177 therein, through the friction plates 178 and 179, the slot 175 of the driver bar, a bearing plate 180 and a leaf spring 181. A nut 182 threaded on the outer end of the screw 176 serves to press the friction plates 178 and 179 against opposite faces of the driver bar 170 so as to provide a yielding frictional engagement between the driver bar 170 and the sliding block 161.

The opposite end of the pin 160 has a reduced diameter portion 185 on which is mounted the lower end of a bar 184. This bar, as shown best

in Figures 4 and 5, is provided with a rearwardly extending pin 186 over which is hooked the lower end of a coil spring 187, the upper end of which is secured as by being passed through a hole therethrough in the extended end portion 188 of the pivot pin 172. This spring 187 yieldingly holds the bar 184 upwardly and thus tends to hold the rivet holder support or slide 153 in its upward position, but is of insufficient strength to retain the holder support 153 in its raised position against the pressure of the rivet driver or set 151 and the frictional engagement between the driver 170 and the friction block 161 when the ram 150 is in driving position or is being moved there-toward.

The bar 184 has threaded in its upper end an adjustable stop screw 190, which, when the ram is depressed, may impinge upon a fixed stop 191 thus to limit the downward motion of the rivet holder slide or support 153, so that after this limit has been reached, further downward motion of the ram 150 causes the driver 170 to slide relative to the block 161. The screw 190 may be fixed in adjusted position by a lock nut 192 threaded thereon and provided with an actuating han-dle 193.

Assuming the driver at its lifted position of Figures 1 and 3, and the work being positioned over the anvil as shown in dash and dotted lines, downward motion of the ram to drive the rivet first causes a downward motion of the slide 161 with the driver 170 until the upper end of the slot 162 strikes the pin 160 (see Figure 4), this motion being sufficient to bring the rivet set or driver 151 down to, or almost to, the head of the rivet supported between the jaws 154 and 155. Further downward motion of the ram then acts to lower the rivet holder support 153 and the jaws 154 and 155 to their desired position just above the work, whereupon the stop screw 190 impinges on the pin 160 as shown in Figure 5, which stops the downward motion of the rivet holder. Continued downward motion of the ram, therefore, produces a sliding between the driver 170 and the slide block 161 to the final driven position of the rivet. On subsequent retracting motion of the ram the parts are returned to their upper position, the extent of return of the block 161 being determined by impingement of its stop screw 165 on the fixed stop 166, the driver 170 sliding relative to the block 161 during the final portion of the upward motion of the ram until its top position is reached where the set 151 is sufficiently lifted to permit a rivet to be fed in beneath it into the position shown in Figure 3 prior to a succeeding setting operation. The spring 187 insures this lifting of the rivet holder support should the friction between the driver 170 and the block 161 be insufficient. The upward limit of motion of the support 153 is determined by the lower face of the sleeve portion 152 against which the support 153 impinges.

The driver 170 for the rivet holder support may also be employed to actuate the rivet separator. Such a separator is shown at 200 in Figure 3, being provided with the usual separator finger 201 forming one portion of an inclined slot 202 through which the rivet must pass as it descends from the raceway 203 to discharged position at the jaws 154 and 155. By moving this separator 200 back and forth, the separator point 201 passes between the two lowest rivets in the slide and allows the lowest rivet, as the separator continues to move to the right in Figure 3, to pass down into driving position in the well understood manner.

As illustrated, this separator 200 is provided with a reduced diameter portion 205 within which is engaged a cam roller 206 at the lower end of an arm 207 of a bell crank lever. This bell crank lever is fulcrumed at 208 and its arm 209 is provided with a pin 210 which passes between the forks 211 (see Figure 1) of a slide block 212. This slide block 212 is provided with a channel portion similar to that of the slide block 161 and the driver 170 is maintained in frictional engage-ment therewith through the friction plates 215 and 216, the pressure plate 217, and the spring 218, in the same manner as has been described with relation to the block 161, and its frictional connections shown as separated in Figure 2. The first portion of the motion of the driver 170 in either direction moves the separator in a corresponding direction throughout the full path of motion of the separator, any further motion of the driver 170 causing slippage of the friction driving connection between the driver 170 and the arm 209.

From the foregoing description of an embodiment of this invention, it should be evident to those skilled in the art that various changes and modifications might be made without departing from the spirit or scope of this invention.

I claim:

1. In a riveting machine, a rivet holder sup-port, a rivet set, means including a ram for actu-ating said set, a sleeve slidably supporting said ram, said rivet holder support having a pair of ex-tensions on opposite sides, a slide carried on one of said extensions, a holder support driving mem-ber secured to said ram and extending along one side of said sleeve and yieldingly engaging said slide, a bar secured at one end to the other of said extensions and lying along the opposite side of said sleeve, a spring securing said bar to said ram for lifting said holder support on re-traction of said ram, and an adjustable stop car-ried by said bar and cooperating with a fixed stop for limiting the downward motion of said holder support as driven by said driving member.

2. In a riveting machine, a rivet holder support, a rivet set, means including a ram for actu-ating said set, a sleeve slidably supporting said ram, said rivet holder support having a guide opening to slidably receive said ram and a pair of ex-tensions on opposite sides, a slide carried on one of said extensions, a holder support driving mem-ber secured to said ram and extending along one side of said sleeve and yieldingly engaging said slide, a bar secured at one end to the other of said extensions and lying along the opposite side of said sleeve, a spring securing said bar to said ram for lifting said holder support on retraction of said ram, and an adjustable stop carried by said bar and cooperating with a fixed stop for limiting the downward motion of said holder support as driven by said driving member.

3. In a riveting machine, a rivet holder sup-port, a rivet holder carried by said support, a rivet set, means including a ram for actu-ating said set to drive a rivet held by said holder, a pin pro-jecting from said holder support, a slide having a slot for interengagement over said pin, a rivet holder support driving member secured to said ram and extending through said slide, friction plates carried by said slide and engaging said driving member, and means for yieldingly pressing said plates against said driving member.

4. In a riveting machine, a rivet holder sup-port, a rivet holder carried by said support, a rivet set, means including a ram for actu-ating said

set to drive a rivet held by said holder, said holder support having a socket portion in which said ram is slidably guided, a slide carried by said holder support, a rivet holder support driving member secured to said ram and in sliding relation to said slide, and a yieldable connection between said slide and said driving member.

5. In a riveting machine, a rivet holder support, a rivet holder carried by said support, a rivet set, means including a ram for actuating said set to drive a rivet held by said holder, said holder support having a socket portion in which said ram is slidably guided, a slide carried by said holder support and having a limited lost motion connection with said holder support, a rivet holder support driving member secured to said ram and in sliding relation to said slide, and a yieldable connection between said slide and said driving member.

6. In a riveting machine, a rivet holder support, a rivet holder carried by said support, a rivet set, means including a ram for actuating said set to drive a rivet held by said holder, said holder support having a socket portion in which said ram is slidably guided, a slide carried by said holder support, a rivet holder support driving member secured to said ram and in sliding relation to said slide, and a frictional connection between said slide and said driving member.

7. In a riveting machine, a rivet holder support, a rivet holder carried by said support, a rivet set, means including a ram for actuating said set to drive a rivet held by said holder, said holder support having a socket portion in which said ram is slidably guided, a slide carried by said holder support, a rivet holder support driving member secured to said ram and in sliding relation to said slide, a yieldable connection between

said slide and said driving member, and stop means for limiting the extent of motion of said holder support with said driving member.

8. In a riveting machine, a rivet holder, a rivet set, means including a ram for actuating said set to drive a rivet held by said holder, a raceway for supplying rivets to said holder, a rivet separator for restricting the feed of rivets from said raceway to said holder to one at a time and a holder-driving member connected to said ram and yieldingly connected to said holder and to said separator.

9. In a riveting machine, a rivet holder, a rivet set, means including a ram for actuating said set to drive a rivet held by said holder, a raceway for supplying rivets to said holder, a rivet separator for restricting the feed of rivets from said raceway to said holder to one at a time, a holder-driving member connected to said ram and yieldingly connected to said holder, and a frictional drive from said member to said separator.

10. In a riveting machine, a rivet holder, a rivet set, reciprocable means for actuating said set to drive a rivet held by said holder, a raceway for supplying rivets to said holder, a rivet separator for restricting the feed of rivets from said raceway to said holder, and a frictional drive for said separator from said actuating means.

11. In a riveting machine, a rivet holder, a rivet set, means including a ram for actuating said set to drive a rivet held by said holder, a raceway for supplying rivets to said holder, a rivet separator for restricting the feed of rivets from said raceway to said holder to one at a time, a reciprocable driving member connected to said ram, and a frictional connection from said member to said separator.

ARTHUR R. HAVENER.
